UNITED STATES PATENT OFFICE.

LOUIS H. BRINKMAN, OF GLEN RIDGE, NEW JERSEY, ASSIGNOR TO BALTIMORE TUBE COMPANY, OF BALTIMORE, MARYLAND, A CORPORATION OF MARYLAND.

METAL-DRAWING MACHINE.

1,143,101.

Specification of Letters Patent. Patented June 15, 1915.

Application filed July 24, 1912. Serial No. 711,203.

To all whom it may concern:

Be it known that I, LOUIS H. BRINKMAN, a citizen of the United States, and a resident of Glen Ridge, in the county of Essex and State of New Jersey, have invented a certain new and useful Improvement in Metal-Drawing Machines, of which the following is a specification.

My invention relates to metal drawing machines and more particularly to machines for drawing metal tubes and rods.

One of the objects of the invention is to provide a durable and efficient machine by which metal tubes or rods of considerable length may be rapidly drawn down to the desired diameter.

Another object of the invention is to provide a metal drawing machine having a rotary ball die and a finishing die through which dies the tubes or rods are drawn, the ball die serving to reduce the diameter of the tube a considerable amount at each draw, while the other die serves to smooth out any unevenness or ball marks in the tubes or rods and give them a good finish and a uniform diameter.

Another object of the invention is to provide a rotary ball die which may be adjusted to given desired diameters, preferably without shutting down the machine, so that after each "draw" the die may be adjusted to reduce its diameter to a given size for the succeeding "draw" without shutting down the machine. The feature of adjusting the diameter of the die during the drawing operation without shutting down the machine enables me to draw tapering tubes or to draw with great accuracy tubes having portions of different thicknesses as may be desired.

My invention will be more readily understood and further objects of the invention will more fully appear from the following description taken in connection with the accompanying drawings forming a part of this specification, and in which—

Figure 1 is a side elevation of a metal drawing machine embodying the preferred form of my invention; Fig. 2 is a top plan view of the same; Fig. 3 is an enlarged elevation of a part of the machine showing the ball die and finishing die in section; and Fig. 4 is a further enlarged sectional view of the ball die showing the manner in which

the die is adjusted according to the preferred form of the invention.

Referring to the drawings (Figs. 1 and 2) 1 is a platform or table on one end of which is mounted a rotary motor 2 adjacent to which a suitable frame 3 is mounted in which the rotary ball die, hereinafter referred to, is journaled. The annular finishing die 4 (hereinafter referred to) is mounted on the table adjacent to the ball die and in alinement therewith, and at the rear of the finishing die a trackway 5 extends along the table in alinement with the dies. A draw head 6 and a following block 7 are mounted on the trackway and a pair of tongs 8 are mounted on the following block with their gripping jaws 9 adapted to grip onto a plug or other suitable means 10 secured in the end of the tube 11 to be drawn, while the other extremity of the tongs is provided with toggle links and a connecting hook 12 connecting the tongs to the draw head 6 which is, in turn, provided with a pivoted hook 13 having a handle 14 by means of which it is lifted into and out of engagement with an endless chain 15 passing over sprocket wheels 16 and 17 mounted near the opposite ends of the table. The chain is driven by means of a suitable motor 18 geared to the sprocket wheel 17 through gear wheels 19, 20, 21 and 22.

When the machine is used for drawing tubes instead of rods, I provide a mandrel 24 which is supported at one end in an open slot 25 in the head of a pillow block 26. The mandrel is preferably of less diameter than the tube to be drawn, and extends through the motor to the ball die, and is provided with an enlarged head 27 resting in the plane of the ball die and of the desired inner diameter of the finished tube.

Referring to Fig. 3, a hollow spindle 28 is journaled in a ring 29 fitting in one end of the supporting frame 3, the journal being provided with ball bearings 30. A die block 31 is keyed on the extremity of the spindle, and is provided with an opening in which suitable relatively adjustable means, such as die cheek plates 32 and 33, are secured by means of keys 34. The cheek plates have their adjacent surfaces suitably grooved to form a raceway having inclined bottom walls 35. Within the raceway there are a series of die balls 36. The inner edges

of the raceway overhang the die balls slightly so as to hold them in position. The cheek plates being keyed to the die block 31, rotate therewith but are relatively adjustable therein axially of the spindle for the purpose of varying the diameter of the die. The adjustment of the cheek plates is accomplished in the present form of my invention, by means of an adjusting device 38 having an annular flanged portion 39 threaded onto an annular extension 40 of the supporting frame 3 which extends out over the die block. The adjusting device, which is in the form of a cap, has an end portion 41 surrounding the end of the die block of the cheek plates and is provided with an opening 42 in alignment with the hollow spindle.

In order to avoid friction between the adjusting device and the adjacent cheek plate 33 in adjusting the die while the machine is in operation, and to take up the thrust from the ball dies, I provide ball bearings 43 between the cheek plate 33 and the surrounding portion 41 of the adjusting device; and I also provide ball bearings 44 between the inner end of the die block and the adjacent wall of the supporting frame 3.

The adjusting device 38 is operated by a handle or pin 46 which is adapted to fit into holes 47 around the circumference of the flange 39 of the adjusting device, by means of which the adjusting device may be screwed in and out along the annular threaded extension 40 of the frame.

If it is desired to reduce the diameter of the die, *i.e.*, the distance between diametrically opposite balls in the raceway, the operator inserts handle 46 in one of the sockets 47 on adjusting cap 38 and rotates it in a direction to move it toward the main frame 3, whereupon the inward thrust of the cap upon bearing plate 33 causes the same to be moved inwardly, thereupon narrowing the tapering raceway, causing the die balls 36 to be forced in to reduce the diameter of the die. Conversely, if it is desired to enlarge the diameter, the operator rotates the adjustable cap 38 in the opposite direction, relieving plate 33 of the thrust, so that when the tube is pulled over the mandrel against the balls, it forces the balls outwardly, thereby shifting the die plate 33 away from the plate 32, so that the raceway is widened and the balls may move outwardly under the pressure from the tube, resulting in enlarging the diameter of the die.

In the present form of my invention the annular flange of the adjusting device and an adjacent part of the stationary frame 3 are provided one with a graduated scale 53 and the other with a pointer 54, whereby the adjusting device may be set within proper limits for any desired diameter to which the tube or rod is to be drawn down.

By this arrangement, each time after the tube has been drawn through the machine, the ball die may be adjusted for the succeeding "drawing" without having to shut down the machine.

In order to efficiently draw tubing or rods with rotary ball dies, it is necessary that the die should rotate at a high speed; and in order to accomplish this purpose and to simplify the machine, I mount the motor 2, as previously mentioned, on a table in alignment with the ball die and connect the rotor 48 of the motor directly to the hollow spindle 28. In the present form of my invention, I use an electric motor to drive the hollow spindle and mount the armature of the motor on an extension 28' of the hollow spindle, the two parts of the spindle being provided with flanges 49 secured together by bolts 50.

The finishing die 4 consists of a frame 51 having an open end in which the die plate 52 is mounted. The opening of the finishing die is annular and tapered in the usual manner and is removably secured in the open end of the frame 51. In operating the machine, a finishing die of the proper diameter may be inserted in the frame 51 for each "drawing", or the finishing die may be omitted until the final "drawing", at which time a die of the desired finished outer diameter of the tube may be inserted. This die serves to smooth out any ball marks or other unevenness or irregularity in the tube so as to give it a good finish and a uniform diameter.

The operation of the embodiment of the invention above described is as follows: The mandrel 24 is lifted out of the socket 25 and the tube 11 to be drawn is slipped over the rear end of the mandrel and through the hollow spindle 28 past the ball die and the finishing die, if one is used in the first "draw", the forward end of the tube being slightly tapered so as to pass through the latter die. The plug 10 is then threaded or otherwise secured into the forward end of the tube, and this plug is gripped by the tongs 8 which are then connected to the draw head 6. The handle 14 of the draw head is then operated to throw the hook 13 into engagement with one of the links of the endless chain 15, and the motor 2 driving the ball die is then started up. The adjusting device 38 is then moved to the desired setting, as indicated by the scale 53, and the motor 18 operating the endless chain is then started, whereupon the tube is drawn forward through the ball die, which reduces the tube to the outer diameter to which the ball die is set. After the tube has been completely drawn through the die, the handle 14 will be thrown back to release the hook 13 on the endless chain, whereupon the ball die is adjusted for the next draw and the tube is released from the tongs and is again

threaded over the tail end of the mandrel and through the hollow spindle and ball die. The draw head and tongs are now moved toward the forward end of the table and the 5 tube is again gripped by the tongs, whereupon the handle 14 is thrown down to engage the hook 13 in the endless chain and the tube is again drawn through the die, and so on until it has been drawn down to the desired diameter.

10 By the provision of means for adjusting the die during the "drawing" operation, tapering tubes can be drawn by varying the diameter of the ball die and shifting the 15 tapered head 27 of the mandrel during the drawing operation, and if desired, tubes of varying thicknesses may be drawn simply by manipulating the adjusting device to reduce or enlarge the diameter of the ball die 20 during the drawing operation. This last feature is useful in drawing boiler tubes, etc.

The head 27 of the mandrel has a short tapering portion of gradually reduced diameter, so that by shifting the head to the left from the position shown in Fig. 3, the extreme end portion of smaller diameter is brought under the die balls so that tubes of 30 smaller inner diameter may be drawn when the head is thus shifted.

25 While I have shown and described my invention in what I believe to be its preferred embodiment, it will be obvious to those skilled in the art that various changes 35 and modifications may be made in the construction and arrangement of the parts without departing from the spirit or scope of the invention, and I do not wish to be understood as limiting myself other than 40 as indicated in the appended claims.

Having thus described my invention, what I claim as new and desire to secure by Letters Patent, is:

1. In a ball die for drawing metal tubes, 45 the combination of relatively adjustable bearings for supporting die balls, a rotatable frame in which said bearings are mounted, means for rotating said frame, a series of die balls mounted on said bearings, 50 a fixed mandrel extending within the die against which the tube is pressed by the balls, means for drawing the tube between the mandrel and the die balls, and means operatively related to said relatively adjustable bearings for adjusting the same one with respect to the other to vary the diameter of the die.

2. In a ball die for drawing metal tubes, 60 the combination of two ball die supporting bearings adjustable one relative to the other longitudinally of the axis of the die and having adjacent surfaces forming a raceway for die balls, die balls mounted in said raceway and adapted to engage the outer, 65 surface of tubes to be drawn, a fixed man-

drel extending within the die, means for producing relative rotation between the mandrel and the ball die bearings, means for drawing the tube between the mandrel and the die balls, and means operatively 70 related to said ball die bearings for adjusting the same one with respect to the other to vary the diameter of the die.

3. In a ball die for drawing metal tubes, 75 the combination of a pair of ball die supporting bearings having annular bearing surfaces for the balls converging from the axis of the die to form a raceway for die balls, said bearings being relatively adjustable axially of the die, die balls mounted 80 in said raceway adapted to engage the outer surfaces of tubes to be drawn, means for rotating the ball die bearings, means for drawing the tubes through the ball die, and means operatively related to said ball die 85 bearings for adjusting the same one with respect to the other to vary the diameter of the die.

4. In a ball die for drawing metal, the combination of adjustable ball-supporting 90 means, a series of balls mounted therein, means for rotating said adjustable ball-supporting means, a non-rotatable frame, and means adjustably mounted on the frame and operatively related to the ball-supporting 95 means to vary the diameter of the die.

5. In a ball die for drawing metal, the combination of two ball-supporting parts relatively adjustable axially of the die, the adjacent faces of said parts forming a 100 raceway therebetween, a series of balls in the raceway, means for rotating said ball-supporting parts, a non-rotatable frame, and a normally stationary adjusting device mounted on the frame and operatively related to one of said relatively adjustable ball-supporting parts to force said part toward the other ball-supporting part to vary 105 the diameter of the die.

6. In a ball die for drawing metal, the 110 combination of a hollow rotatable spindle, adjustable ball-supporting means carried on the spindle, a series of balls mounted in said means, and means operatively related to said adjustable ball-supporting means for 115 adjusting the same to vary the diameter of the die.

7. In a ball die for drawing metal, the combination of a hollow rotatable spindle, 120 ball-supporting means carried on the spindle and comprising two relatively adjustable parts, a series of balls mounted in said means, a non-rotatable frame, and means adjustably mounted on the frame and operatively related to one of the ball-supporting parts to move the same to vary the diameter of the die.

8. In a ball die for drawing metal, the combination of a hollow rotatable spindle, 125 two ball-supporting parts carried by the 130

- spindle and relatively adjustable axially thereof, the adjacent surfaces of said parts being shaped to form a raceway therebetween with an inclined wall, a series of balls 5 in the raceway, a stationary frame, and a normally stationary adjusting device mounted on the frame and operatively related to one of said relatively adjustable ball-supporting parts to force it toward the other 10 part so as to narrow the raceway and force the balls inward to vary the diameter of the die.

9. In a ball die for drawing metal, the combination of a hollow rotatable spindle, 15 two ball-supporting parts carried by the spindle and relatively adjustable axially thereof, the adjacent surfaces of said parts being shaped to form a raceway therebetween with an inclined wall, a series of balls 20 in the raceway, a stationary frame, and means adjustably mounted on the frame and operatively related to one of said relatively adjustable ball-supporting parts to force it toward the other part so as to narrow the 25 raceway and force the balls inward to vary the diameter of the die.

10. In a ball die for drawing metal, the combination of a hollow rotatable spindle, two ball-supporting parts carried by the 30 spindle and relatively adjustable axially thereof, the adjacent surfaces of said parts being shaped to form a raceway therebetween with an inclined wall, a series of balls in the raceway, a stationary frame, a normally 35 stationary adjusting device operatively related to one of said relatively adjustable ball-supporting parts to force it toward the other part, and ball bearings between said adjusting part and said ball- 40 supporting part for receiving the thrust from the ball dies.

11. In a ball die for drawing metal, the combination of a hollow rotatable spindle, two ball-supporting parts carried by the 45 spindle and relatively adjustable axially thereof, the adjacent surfaces of said parts being shaped to form a raceway therebetween with an inclined wall, a series of balls in the raceway, a stationary frame, means 50 adjustably mounted on the frame and having a part surrounding the end of the die toward which the metal is drawn, and ball bearings between said surrounding part and the adjacent ball-supporting part for taking 55 up the thrust from the ball dies.

12. In a ball die for drawing metal, the combination of a hollow rotatable spindle, two ball-supporting parts carried by the spindle and relatively adjustable axially 60 thereof, the adjacent surfaces of said parts being shaped to form a raceway therebetween with an inclined wall, a series of balls in the raceway, a stationary frame, a normally stationary adjusting device having a 65 part surrounding the end of the die toward

which the metal is drawn, and ball bearings bearings between said surrounding part and adjustable ball-supporting part for taking up the thrust from the ball dies.

13. In a ball die for drawing metal, the 70 combination of a stationary frame, a hollow rotatable spindle journaled in the frame, adjustable ball-supporting means carried on the spindle, a series of balls mounted in said means, and means adjustably mounted on 75 the frame and operatively related to said adjustable ball-supporting means for adjusting the same to vary the diameter of the die.

14. In a ball die for drawing metal, the 80 combination of a hollow rotatable spindle, a frame in which the spindle is journaled, a die-block carried at one end of the spindle and having an opening therein in alignment with the spindle, die cheek plates 85 mounted in said opening and relatively adjustable axially of the spindle and having an opening therethrough concentric with the spindle, a raceway for die balls formed in the adjacent surfaces of the plates and 90 having an inclined wall, a series of balls in said raceway, and an adjusting device operatively related to one of the cheek plates for moving it axially to vary the diameter of the die.

95
15. In a ball die for drawing metal, the combination of a hollow rotatable spindle, a frame in which the spindle is journaled, a die-block carried at one end of the spindle and having an opening therein in alignment 100 with the spindle, die cheek plates mounted in said opening and relatively adjustable axially of the spindle and having an opening therethrough concentric with the spindle, a raceway for die balls formed in the 105 adjacent surfaces of the plates and having an inclined wall, a series of balls in said raceway, a normally stationary adjusting device having a part surrounding the end of the die and operatively related to one of the cheek plates for moving the same 110 axially, and ball bearings between said cheek plates and the adjacent part of the adjusting device.

115
16. In a ball die for drawing metal, the combination of a hollow rotatable spindle, a die-block carried at one end of the spindle and having an opening therein in alignment with the spindle, die cheek plates mounted in said opening and relatively adjustable 120 axially of the spindle and having an opening therethrough concentric with the spindle, a raceway for die balls formed in the adjacent surfaces of the plates and having an inclined wall, a series of balls in said raceway, a frame having a hollow threaded portion concentric with the spindle, and an adjusting device threaded on said portion and having an opening therein also concentric with the spindle, said device being op- 125
130

eratively related to one of the cheek plates to move the same axially to vary the diameter of the die.

17. In a ball die for drawing metal, the combination of a hollow rotatable spindle, a rotary motor having its rotatable member directly connected to said spindle for driving the same, adjustable ball-supporting means carried on the spindle, a series of balls mounted in said means, and means operatively related to said adjustable ball-supporting means for adjusting the same to vary the diameter of the die.

18. In a ball die for drawing metal, the combination of a hollow rotatable spindle, a rotary motor having its rotatable part directly connected to said spindle, two ball-supporting parts carried by the spindle and relatively adjustable axially thereof, the adjacent surfaces of said parts being shaped to form a raceway therebetween with an inclined bottom wall, a series of balls in the raceway, a stationary frame, and a normally stationary adjusting device adjustably mounted on the frame and operatively related to one of the adjustable ball-supporting parts to force it toward the other part so as to narrow the raceway and force the balls inward to vary the diameter of the die.

19. In a ball die for drawing metal tubing, the combination of a hollow rotatable spindle, a rotary motor having its rotatable part mounted on the hollow spindle, two ball-supporting parts carried by the spindle and relatively adjustable axially thereof, the adjacent surfaces of said parts being shaped to form a raceway therebetween with an inclined wall, a series of balls in the raceway, a stationary frame, a normally stationary adjusting device adjustably mounted on the frame and operatively related to one of the adjustable ball-supporting parts to force it toward the other part so as to narrow the raceway and force the balls inward to vary the diameter of the die, and a mandrel extending through the rotatable part of the motor and the spindle and having a part surrounded by the die balls and against which the die balls force the tube.

20. In a ball die for drawing metal tubing, the combination of a hollow rotatable spindle, a frame in which the spindle is journaled, a rotary motor having its rotatable part mounted on the hollow spindle, a die-block carried at one end of the spindle and having an opening therein in alinement with the spindle, die cheek plates mounted in said opening and relatively adjustable axially of the spindle and having an opening therethrough concentric with the spindle, a raceway for die balls formed in the adjacent surfaces of the plates and having an inclined wall, a series of balls in said raceway, an adjusting device operatively

related to one of the cheek plates for moving it axially to vary the diameter of the die, and a mandrel extending through the rotor of the motor and through the spindle and having a part surrounded by the die balls and against which the tube is forced.

21. In a ball die for drawing metal tubing, the combination of a hollow rotatable spindle, a rotary motor having its rotatable part directly connected to the spindle, adjustable ball-supporting means carried on the spindle, a series of balls mounted in said means, means operatively related to said adjustable ball-supporting means for adjusting the same to vary the diameter of the die, and a mandrel extending through the motor and the spindle and having a part surrounded by the die balls and against which the die balls force the tube.

22. In a ball die, the combination of a rotatable hollow spindle, a frame in which the spindle is journaled, said frame having a threaded annular part, die cheek plates carried at the end of the spindle and relatively movable axially thereof and having an opening therethrough concentric with the spindle, the adjacent faces of the cheek plates forming a raceway having an inclined wall, a series of ball dies in said raceway, an adjusting device having a flange threaded on the annular part of the frame and having a portion surrounding the end of said frame and provided with an opening in alinement with the hollow spindle, and ball bearings fitting between said adjusting device and the adjacent cheek plate to take the thrust from the die balls.

23. In a ball die, the combination of a rotatable hollow spindle, a frame in which the spindle is journaled, die cheek plates carried at the end of the spindle and relatively movable axially thereof and having an opening therethrough concentric with the spindle, the adjacent faces of the plates forming a raceway having an inclined wall, a series of die balls in said raceway, an annular flange on the supporting frame surrounding the spindle and cheek plates, ball bearings between the frame and the adjacent cheek plate, a cap piece threaded on the annular flange of the frame and having an opening in alinement with the spindle, and ball bearings between the cap piece and the adjacent cheek plate for receiving the thrust from the ball dies.

24. In a ball die, the combination of an elongated hollow spindle, a frame in which the spindle is journaled, a die block carried at the end of the spindle, cheek plates mounted in said block and relatively movable axially of the spindle and having an opening therethrough concentric with the spindle, the adjacent faces of the plates forming a raceway having an inclined wall, a series of die balls in said raceway, an an-

- nular flange on the frame surrounding the spindle and cheek plates, ball bearings between the frame and the adjacent cheek plate, a cap piece threaded on the annular flange of the frame and having an opening in alinement with the spindle, and ball bearings between the cap piece and the adjacent cheek plate for receiving the thrust from the ball dies.
- 10 25. In a machine for drawing metal tubing, the combination of a hollow rotatable spindle, adjustable ball-supporting means carried on the spindle, a series of balls mounted in said means, means operatively related to said adjustable ball-supporting means for adjusting the same to vary the diameter of the die, a rotary motor having its rotatable member directly connected to said spindle for driving the same, a table, a trackway on the table, a draw head adapted to move on the trackway, means for connecting the draw head with the tube, means for moving the draw head along the trackway, a mandrel extending through the motor and hollow spindle and having a part surrounded by the die balls and against which the tube is forced, and a support for the rear end of the mandrel in which it is removably held.
- 15 20 25 30 26. In a machine for drawing metal tubing, the combination of a table, a hollow rotatable spindle mounted on said table, a rotary motor also mounted on the table and having its rotatable part directly connected to the spindle, adjustable ball-supporting means carried on the spindle, a series of balls mounted in said means, means operatively related to said adjustable ball-sup-

porting means for adjusting the same to vary the diameter of the die, a mandrel extending through the motor and the hollow spindle and having a part surrounded by the die balls and against which the balls force the tube, a trackway on the table arranged longitudinally thereof, a draw head adapted to move in said trackway, means for connecting said draw head to the tube, and means for moving the draw head along the trackway.

27. In a ball die for drawing metal, the combination of a hollow rotatable spindle, a rotary motor connected to said spindle, two ball-supporting parts carried by the spindle and relatively adjustable axially thereof, the adjacent surfaces of said parts being shaped to form a raceway therebetween with an inclined wall, a series of balls in the raceway, a stationary frame, and a normally stationary adjusting device adjustably mounted on the frame and operatively related to one of the adjustable ball-supporting parts to force it toward the other part so as to narrow the raceway and force the balls inward to vary the diameter of the die, said frame and adjusting device having a scale and marker whereby the adjusting device may be set at any desired position while the machine is in operation.

In testimony whereof, I have signed my name to this specification, in the presence of two subscribing witnesses.

LOUIS H. BRINKMAN.
